Primary Examiner — Janice Hallmark*Assistant Examiner* — Harold E Blackwell, II(74) *Attorney, Agent, or Firm* — AP Patents(57) **CLAIM**

The ornamental design for a pegboard adapter, as shown and described.

DESCRIPTION

The present application closely relates to co-pending U.S. nonprovisional patent application Ser. No. 15/336,039, titled “Pegboard adapter and Method” and filed concurrently herewith by inventors Eshan Gupta and Anil Gupta. FIG. 1 is a perspective view of a pegboard adapter showing my new design.

FIG. 2 is a front view of the pegboard adapter of FIG. 1. FIG. 3 is a rear view of the pegboard adapter in FIG. 1. FIG. 4 is a top view of the pegboard adapter in FIG. 1. FIG. 5 is a bottom view of the pegboard adapter in FIG. 1; and, FIG. 6 is a left view of the pegboard adapter in FIG. 1. The right side view is a mirror image. The pegboard adapter is shown with a symbolic break in its height. The appearance of any portion of the article between the break lines forms no part of the claimed design.
